UNITED STATES PATENT OFFICE.

MERCY E. BAKER, OF WESTPORT POINT, MASSACHUSETTS.

MOLD.

1,243,128.

Specification of Letters Patent. Patented Oct. 16, 1917.

Application filed November 15, 1916. Serial No. 131,534.

To all whom it may concern:

Be it known that I, MERCY E. BAKER, a citizen of the United States, residing at Westport Point, in the county of Bristol 5 and State of Massachusetts, have invented certain new and useful Improvements in Molds, of which the following is a specification.

This invention relates to molds and more 10 particularly to a spherical-shaped mold for receiving and compressing paper pulp or the like whereby compressed spherical units may be formed for utilizing paper as a fuel.

One of the objects of the invention is to 15 provide two coöperating hemispherical members having means whereby they may be manually pressed into engagement with each other for compressing a fibrous or pulpos mass into a compact unit, the hemispherical members being provided with a plurality of apertures whereby the moisture may be excluded from the mass while the same is being compressed.

A further object of this invention is the 20 provision of a mold which consists of comparatively few parts and is simple in construction, but durable and well adapted to withstand the rough usage to which devices of this character are ordinarily subjected.

For a full description of the invention 25 and the advantages and merits thereof, reference is to be had to the following description and the accompanying drawings, wherein is illustrated the preferred form

30 of my invention, in which;

Figure 1 is a top plan.

Fig. 2 is a section on the 2—2 of Fig. 1.

It has been demonstrated that old newspapers or other similar waste paper may be 35 utilized for fuel for heating or cooking purposes by first soaking the waste paper in water and then compressing portions of the pulpos mass thus formed until the moisture is excluded. In order that the mass may

40 be thoroughly compressed and freed from moisture, at the same time formed into a unit of uniform configuration, the device herein described is constructed to form the mass into a compact sphere. Therefore, I

45 have provided two hemispherical portions 1 and 2 which constitute the main portion of the mold. For the purposes of this description the halves of the mold are designated as the upper mold 2 and the lower mold 1.

50 The peripheral edge of the lower mold 1 is provided with an annular groove 3 and the

outer wall of the groove thereby forms the annular flange 4 extending completely around the proximate edge of the lower mold 1. 60

The proximate edge of the upper mold 2 is adapted to fit within the annular groove 3 when the upper and lower molds are in closed position. It is to be observed that the proximate edges of the upper and lower 65 molds are extended slightly beyond the diametrical center line of its respective mold thus permitting the edges to overlap as clearly shown by Fig. 2 of the drawing. By virtue of the edge of the upper mold fitting 70 in the annular groove 3, a perfectly spherical interior is provided thus assuring a perfectly spherical and compact unit.

Projecting from the edge of the lower 75 mold 2 is a pair of ears 5 having apertures formed therein while the upper mold is provided with a lug or ear 6 adapted to be disposed between the lugs 5 and has the central opening arranged in alinement with the openings in the ears 5. A hinged pin or 80 pindle 7 is projected through the openings thereby providing a hinge for opening and closing the mold.

At the opposite edge of each mold is a 85 handle 8 and it will be noted that the handle of the upper mold is adapted to extend into a notch 9 formed in the annular flange 4 of the lower mold thereby permitting the handles to be moved into close relation when compressing the mold. As shown by Fig. 1 90 of the drawing the handles 8 are spaced apart with respect to their lateral disposition thereby permitting the handles to move into closer relationship for closing the upper and lower molds together as clearly 95 shown by Fig. 2 of the drawing. Each element of the mold is provided with a plurality of openings 10 for permitting the water and moisture to escape from the 100 pulpos mass when the same is being compressed.

It is pointed out that the formation of a spherical inflammable unit for fuel purposes will, by virtue of its spherical formation, burn evenly and uniformly thereby 105 resulting in the maximum heat being obtained when a number of the units are being consumed. Furthermore the formation of a spherical unit from a pulpos watery mass will be more readily drained of water 110 and moisture than would a unit of any other formation.

From the foregoing it will be observed that a very simple and durable mold has been provided, the details of which embody the preferred form. I desire it to be understood however, that slight changes in the minor details of construction may be made without departing from the spirit of the invention or the scope of the claims hereunto appended.

10 I claim:

1. A mold comprising a hollow body divided into two hemispherical mold sections, each being perforated with a plurality of openings, the marginal edges of each of the 15 sections being adapted to contact for tightly closing the interior of the hollow body for forming a perfectly spherical mold chamber, the marginal edge of one of the sections having an annular flange adapted to engage the marginal edge of the corresponding section on the exterior thereof, handles carried by each of the sections, the said flanges being adapted to move toward or 20 away from each other, the said flange having a notch provided in the path of move- 25

ment of one of the handles whereby they may be moved into close proximity for closing the said sections, and hinges connecting the said sections.

2. A mold comprising a body divided into upper and lower hemispherical mold portions, the edge of one of the mold portions being provided with an annular groove, the outer wall of the groove forming a flange on the edge of the said mold portion, the edge of the corresponding portion being adapted to fit within the said groove for providing a perfectly spherical interior when the said mold portions are moved into engagement with each other, handles carried by each of the portions, and adapted to move into close relation for closing the said mold, the said flange having a notch for receiving one of the said handles.

In testimony whereof I affix my signature in presence of two witnesses.

MERCY E. BAKER.
